United States Patent Office

Des. 190,553
Patented June 13, 1961

190,553

ROBE

Dorothy Jeanne Oakley, Chicago, Ill., assignor to E. R.
Moore Co., Chicago, Ill., a corporation of Illinois

Filed Oct. 20, 1959, Ser. No. 57,981

Term of patent 14 years

(Cl. D3—26)

FIG. 1.

FIG. 2.

The essential features of my design reside in the solid line disclosure in the drawing.

I claim:

The ornamental design for a robe, as shown and described.
